UNITED STATES PATENT OFFICE.

RICHARD BASCOMB WARRINER, OF CORINTH, MISSISSIPPI.

SYRINGE.

Application filed March 7, 1924. Serial No. 697,547.

To all whom it may concern:

Be it known that I, RICHARD B. WARRINER, a citizen of the United States, residing at Corinth, in the county of Alcorn and State 5 of Mississippi, have invented certain new and useful Improvements in Syringes; and I do hereby declare the following to be a full, clear, and exact description of the invention, such as will enable others skilled in 10 the art to which it appertains to make and use the same.

This invention relates to an improvement in syringes and more particularly syringes utilizing glass pump elements.

15 An object of the present invention is to provide an improved holder having means for snugly supporting the barrel of the pump and also for securing the usual nipple of such pumps in alignment with the syringe 20 needle without any lateral strains on said nipple and entirely relieving the pump part from the thrust of the needle.

Further objects will more particularly appear in the course of the following detailed description.

The invention consists in the novel construction, arrangement and combination of parts as hereinafter more particularly described and claimed.

30 One sheet of drawings accompanies this specification as part thereof in which like reference characters indicate similar parts throughout, and in which,—

Figure 1 is a side elevation partly broken 35 away illustrating the improved device;

Fig. 2 is a transverse cross sectional view taken on line 2—2 of Figure 1;

Fig. 3 is a bottom view with the needle removed;

40 Fig. 4 is a detail vertical cross sectional view illustrating a slightly modified form; and

Fig. 5 is a transverse cross sectional view taken on substantially the same line as Fig. 45 2 but illustrating a modified form.

In accordance with the present invention two or more spaced members 1 are provided, preferably of arcuate cross section bridged at one end and provided at the other end with laterally projecting finger clasps 2—2. The lower or projected end is provided with an orifice 3 and the inner face of the bridge part is provided with a plurality of radially projecting key seats 4 extending from the orifice 3. The members 1—1 are adapted to snugly embrace the barrel 13 of the glass

pump which, as is customary, is provided with a nipple 12.

A bushing 5 is provided adapted to seat loosely in the orifice 3 so as to have ample 60 room for lateral adjustment within the said orifice. This bushing 5 is provided on its inner face with radially projecting lugs 6—6 which are adapted to seat in the key seats 4 provided in the bridge part of the 65 holder. The bushing 5 is further provided with a central orifice threaded as at 8 and the bushing is secured in its position in orifice 3 by pins 7—7 extending through suitable holes provided in the members 1—1, 70 said pins being adapted to engage over the lugs 6—6, as is well illustrated in Figs. 2, 4, and 5.

The present invention is particularly adapted to be used with my improved needles as disclosed in my pending application, 75 Serial No. 484,248, which consists of a needle proper 14 secured to a body part 9 from which projects a lug 10 exteriorly threaded and provided with a socket seat 80 adapted for slip joint connection with the nipple 12 of the pump. The exterior threads of the needle are adapted to co-mate with the threads 8 of the orifice in the bushing 5.

Any number of lugs 6—6 may be provided 85 or, if preferred, a plurality of bushings may be associated as is illustrated in Figs. 4 and 5 where are shown two bushings 5 and 5', the bushings being arranged so that the lugs 6—6 are in opposed relation to the lugs 6'—6' of the bushing 5'. Such an association of bushings permits a wider range of adjustment, as obviously one or more of the exterior bushings may be omitted as desired.

In operation it will be apparent that with 95 the structure thus described the nipple 12 of the glass pump will seat snugly in the socket seat 11 of the needle without any lateral strains thereon, while at the same time the thrust of the needle 14 is transmitted directly through pins 7—7 to the holder members 1—1 and thence to the finger clasps 2—2 so that the glass pump of the device is entirely relieved of any lateral or longitudinal strains, thus reducing the liability of 105 fracturing the glass barrel to a minimum.

Modifications will readily suggest themselves to those skilled in the art but within the scope of the present invention as claimed.

Having thus fully described my invention, what I claim as new and desire to se-

2
cure by Letters Patent of the United States
is,—

1. The combination of a syringe holder comprising two spaced pump engaging members bridged at one end, said bridge having an orifice, bushing adapted to seat in said orifice with lateral play and lateral play only, said bushing provided with an orifice adapted to seat a needle, and a needle having a body adapted to seat in the bushing and provided with a slip joint seat for the nipple of a pump.

2. The combination of a syringe holder comprising two spaced members adapted to engage a pump barrel snugly, said members bridged at one end, the bridge being provided with an orifice, and a laterally adjustable bushing adapted to seat in said orifice and to hold a needle and the nipple of the pump, with means to secure said bushing against longitudinal movement relative the axis of the holder.

3. The combination of a syringe holder comprising two spaced members adapted to engage a pump barrel snugly, said members bridged at one end, the bridge being provided with an orifice, a non-rotatable, laterally adjustable bushing adapted to seat in said orifice, said bushing provided with a

threaded orifice, a syringe needle having a body part exteriorly threaded to seat in the orifice of the bushing, said body of the needle having a slip joint seat communicating with the conduit of the needle adapted to seat the pump nipple, and means for directing the thrust of the needle through the bushing to the holder.

4. The combination of a syringe holder comprising spaced members adapted to snugly engage a pump barrel, said members bridged at one end and the bridge provided with an orifice having radially projecting key seats, and a bushing having a radially projecting key, said bushing adapted to seat in said orifice of the bridge part with lateral play in all directions and constructed to secure a needle and the nipple in alignment.

5. The combination of spaced members adapted to snugly engage a pump barrel, said members bridged at one end and the bridge provided with an orifice, a bushing adapted to seat in said orifice with lateral play, and thrust receiving members carried by said spaced members adapted to engage the bushing to transmit longitudinal thrust thereon to said spaced members.

In testimony whereof I affix my signature.
RICHARD BASCOMB WARRINER.
